UNITED STATES PATENT OFFICE.

LOUIS R. SIROIS, OF PORTLAND, MAINE.

EVEN FEED GREASE RESERVOIR.

Application filed March 13, 1925. Serial No. 15,277.

To all whom it may concern:

Be it known that I, LOUIS R. SIROIS, a citizen of the United States, residing at Portland, in the county of Cumberland and State 5 of Maine, have invented certain new and useful Improvements in an Even Feed Grease Reservoir, of which the following is a specification.

The present invention relates to a grease 10 reservoir and has for its principal object to provide means for feeding the grease therefrom at a constant rate at all times.

Another important object of the invention 15 is to provide a grease reservoir structure wherein a container is provided with a spring actuated follower and a valve which is opened as the tension or force of the spring becomes less as the container is emptying.

20 A further general object of the invention is to provide a device of this nature with a simple structure which will prove efficient and reliable in operation, one which may be manufactured at a comparatively low cost 25 and yet be strong, durable, not liable to readily get out of order, easy to fill, and otherwise well adapted to the purpose for which it is designed.

With the above and numerous other objects in view as will appear as the description 30 proceeds, the invention resides in certain novel features of construction, and in the combination and arrangement of parts as will be hereinafter more fully described and 35 claimed.

In the drawing:—

Figure 1 is a vertical longitudinal section through the device embodying my invention.

Figure 2 is a section through the valve 40 thereof.

Figure 3 is a detail sectional view showing one of the cam supports, and

Figure 4 is a detail view showing one of the cams for operation of the valve.

45 Referring to the drawings in detail it will be seen that 1 designates a container having its top closed by a screw cap 2. The bottom of the container is provided with screw threaded opening for receiving the valve casing 3. A transverse opening 4 is provided in the side of the container adjacent the bottom for receiving the lower end of an upstanding pipe 5 having a check valve structure 6 therein. The upper end of this pipe 5 may be closed by a suitable cap 7. This pipe 5 is used for filling purposes as

will be brought out more clearly hereinafter. A follower 8 is slidable in the container 1 and is urged downward toward the bottom thereof by a spring 9. This spring 9 60 is of the coiled type and has one end impinging against the cap 2 and the other against the follower 8. A washer 10 is mounted on the under face of the follower 8 so as to prevent leakage between the edge thereof and 65 the inner surface of the container 1. Rods 11 are attached to the follower 8 and project through openings 12 in the cap 2. Arms 13 are slotted as at 14 for receiving pins 15 at the upper ends of the rods 11. Balls 16 are 70 formed on the ends of the arms 13 and have offcenter dentures 17 provided therein for receiving trunnions 18 and 19 carried by the brackets 20. The trunnions 19 are threadedly engaged in the brackets 20 so that the 75 balls 16 may be readily engaged and disengaged. The arms 13 will rock the balls 16 and because of their off center mounting it will be seen that they will act as cams.

A valve seat 21 is mounted in the valve 80 casing 3, and a valve 22 is slidable in this casing for seating against the seat 21. This valve 22 is provided with a diagonally arranged opening in its end as at 23. The upper end of the valve 22 is reduced and 85 threaded as at 24. A stem 25 threadedly engages the reduced portion 24 and extends slidably through the follower 8 and through the cap 2 terminating in a knob 26 having an annular groove 27 therein. The balls 16 90 are mounted in this annular groove 27. A cover 29 is threadedly engaged with the cap 2 and covers the parts thereabove.

When it is desired to fill the container 95 after it has been emptied, it will be seen that the follower 8 is resting on a cross member 30 which projects through a slot 31 in the valve 22 to prevent turning of the valve. A grease gun or the like is engaged with the end of pipe 5 and the knob 26 turned 100 in a counter-clockwise direction so as to move the valve 22 away from the stem 25 so as to close it against the seat 21. By operation of the grease gun the grease will fill the container 1 under the follower 8 105 raising the latter so as to compress the spring 9. The grease reservoir is now ready for operation and by turning the knob 26 in a clockwise direction the valve may be opened the sufficient degree so that the follower 110 will force the grease therethrough. As this follower moves downwardly in the container

the spring 9 will lose of its tension and therefore I provide means for opening the valve slightly so as to compensate for this loss of tension of the spring so that an even flow of grease will proceed through the valve. This means includes the rods 11, arms 13, and the balls 16. As the rods 11 move downwardly with the follower 8 the balls or cams 16 will rotate in the grooves 27 from the position as shown in Figure 4 and will therefore raise the knob 26, the stem 25, and the valve 22 so as to enlarge the opening therethrough. In other words the further the follower 8 moves downwardly in the container 1 the opening will become larger in the valve, thereby compensating for the loss of tension in the spring 9 so as to maintain an even flow of grease from the container.

From the above it will be apparent that I have devised a grease cup or reservoir which will automatically operate to feed an even amount of grease to the bearing or other part with which it is associated no matter how much grease may be contained therein. The present embodiment of the invention has been disclosed merely by way of example and attains all the features of advantage enumerated as desirable in the statement of the invention and the above description, but it is desired to point out that numerous changes in the details of construction and in the combination and arrangement of parts may be resorted to without departing from the spirit or scope of the invention as herein-after claimed or sacrificing any of its advantages.

Having thus described the invention, what I claim is:—

1. In a grease reservoir, a spring actuated 40 discharge follower, a valve, a stem for operation of the valve having an annular groove at its top and passing through the follower, a cam rotatable in the groove for lifting the stem and opening the valve, and 45 means operatively connected to said follower, and to said cam whereby the follower will control the valve so that said valve will be open to a greater extent as the spring loses its tension. 50

2. In a grease reservoir, a discharge follower, a spring for operation of the follower, a valve for controlling the discharge of grease from the container, a stem connected to the valve, said stem being provided with an annular groove, a cam rotatable in the annular groove, an arm for operation of the cam, a rod extending from the follower, and a pin and slot connection between the arm and rod. 55

3. In a grease reservoir, a discharge follower, a spring for operation of the follower, a valve for controlling the discharge of grease from the container, a stem connected to the valve, said stem provided with an annular groove, a cam rotatable in the annular groove, an arm for operation of the cam, a rod extending from the follower, and a pin and slot connection between the arm and rod, said valve having a threaded extension for engaging said stem so that by rotation of the stem said valve may be closed. 60

In testimony whereof I affix my signature.
LOUIS R. SIROIS.
